WINDER.

No. 806,065.

Specification of Letters Patent.

Patented Nov. 28, 1905.

Application filed April 17, 1905. Serial No. 266,149.

To all whom it may concern:

Be it known that I, CLARENCE N. CHILDS, a citizen of the United States, residing at Lowell, in the county of Middlesex and Commonwealth of Massachusetts, have invented a certain new and useful Improvement in Winders, of which the following is a specification.

This invention relates to winders or machines for winding yarn (or thread) upon cop-holders—as bobbins, tubes, cones, or spindles—into conical cylindrical cops or other packages.

Usually in machines of the kind herein described the yarn is drawn by the rotation of a cop-holder—as a bobbin, tube, or cone—through a tension device commonly called "the tension," through a drop or drop-wire suspended on the yarn, and through a traversing yarn-guide to said cop-holder. When the yarn in such a machine is exhausted or broken between the tension and the cop-holder, the drop falls into the path of a moving piece and is thereby moved to effect or permit the operation of the stop-motion. In winding-machines of the class referred to the cop-holder and cop are usually rotated by frictional contact with a positively-driven drum and the stop-motion is operated not to stop the drum, but to raise the cop out of such contact. Sometimes a yarn-scaper is interposed between the drop and the yarn-guide proper to remove lint, waste, and short pieces of yarn from the yarn being wound and to arrest knots of such a size as to interfere with the subsequent uses of the yarn—in hosiery-yarn, for instance, to prevent knots too large to pass through the needles of a knitting-machine from being wound into the cop. This yarn-scaper is commonly called a "yarn-guide;" but from its function in the machine hereinafter described it might properly be called a "yarn-scaper and knot-arrester." Said guide, scraper, or catcher consists of two plates arranged in the same plane and slightly separated to scrape or clean the yarn passing between said plates and to prevent the passage between them of a knot or bunch exceeding a predetermined size. Where a knot or bunch is stopped by the yarn-scaper, the yarn is broken between the scraper and the cop; but the knot or bunch frequently becomes wedged between the plates, so that the yarn is held stretched between the scraper and the tension device and does not permit the falling of the

drop-wire and the operation of the stop-motion. The cop is therefore not lifted out of contact with the driving-drum and continues to revolve, which causes a softening of the outside of the cop, frequently rendering it necessary to unwind and rewinding a part of the cop. When the cop is not raised from the drum by the stop-motion, there is nothing to indicate to the attendant, without a careful inspection, that the yarn is broken. It will be understood that there are a plurality of driving-drums and cops in a single "frame" or machine—in the largest machines as many as one hundred drums, arranged fifty on a side—thus making the machine from thirty to forty feet in length, so that if the operative is busy in piecing up the broken yarns at one end of the winder it would be impossible for her to see the broken yarns at the other end on the same side or to see broken threads on the other side of the machine at a comparatively short distance away. Hence the cop is likely to revolve for a considerable time after the yarn is broken between the yarn-scaper and the cop. The use of the yarn-scaper, therefore, to a great extent prevents the operation of the stop-motion.

I provide means for permitting the fall of the drop-wire when a knot or bunch in the yarn is wedged in the yarn-scaper in such a manner as to prevent the weight of the drop from drawing the broken end of the yarn back through said scraper, as would happen if the yarn were not so wedged. I cause the tension device to vibrate continuously toward and from the drop-wire at a rate of movement less than the usual movement of the yarn toward and through the scraper, so that when the yarn is passing properly through the scraper the winding of the yarn on the cop will prevent the yarn between the scraper and the tension device from slackening sufficiently to lower the drop-wire. When the yarn stops running through the scraper, the approach of the tension device toward the drop-wire slackens the yarn and allows the drop-wire to fall.

In the accompanying drawings, Figure 1 is a transverse section of a part of a winder, showing in side elevation all the parts necessary to the understanding of this invention; Fig. 2, a front elevation of the drop-wire and its holder; Fig. 3, a front elevation of a yarn-scaper; Fig. 4, a front elevation of a tension device and its supporting rock-shaft.

The frame A, main shaft B, band-pulley C, driving-drum D, driven by a band d from the pulley C and represented as conical, but in practice frequently cylindrical, the cop E, 5 supported and rotated by frictional contact with the drum D, said cop being represented as conical, but in practice frequently cylindrical, the cradle e, which supports the spindle e' of the cop and which swings about its axis e^2 as the cop enlarges and also to lift the cop 10 out of contact with the drum D, the lever F, turning on a fixed axis f and carrying a weight f' at one end and at the other end at f^2 bearing against the under side of the cradle e, the 15 stop-motion slide G, pivoted at g to the lever F between the fulcrum f and the weight f' and supported in a stationary fork a^2 , which permits the longitudinal movement of said slide—these parts are all of the usual construction 20 and operation, a bolt g^2 , adjustable in the slot g' , securing to said slide a downhanging arm g^3 , having a lateral extension g^4 , the front of which normally rests against the rear end of the normally horizontal part h of the drop-wire holder h' , as indicated by full lines in 25 Fig. 1, the drop-wire H having a vertical pivot-slot h^2 , which allows it to be held out of the path of the projections j on the knock-off wheel J, driven by a belt j' from a pulley j^2 on the 30 main shaft. The yarn-guide K, caused to traverse by the usual means to distribute the yarn over the length of the cop E, the yarn-scaper, and knot-catcher L, also commonly called a 35 "yarn-guide" and consisting of two plates l^1 , lying in the same substantially vertical plane and separated by a narrow horizontal slit l^2 , through which the yarn passes from the drop-wire, the tension device M, Fig. 4, represented as consisting of two disks m m' , 40 pressed against a yarn N, passing between them by a spring m^2 , are all of the usual construction and operation except as hereinafter specified.

The lower plate l^1 of the yarn-scaper is 45 movable in the usual manner to allow the thread to be passed through the yarn-scaper.

The tension-disks m m' are supported on a horizontal rod m^3 , which projects horizontally from a bracket m^4 , rigidly secured to the 50 horizontal tension-rail m^6 , which is usually immovably held from turning.

The yarn passes from a skein, ball, or from a bobbin O, as herein represented, between the tension-disks m m' through an eye h^3 , 55 with which the upper end of the drop-wire H is provided, through a knot-scaper L and yarn-guide K to the cop E, the drop-wire being held in the position shown in full lines in Fig. 1 by the tension of the yarn between the 60 tension device and the cop.

Instead of a stationary tension-rail m^6 I use a rock-shaft—that is, I arrange said rail to turn in the brackets a , which commonly support said rail, (only one such bracket a being 65 shown,) and I provide said rail with a radial

arm m^7 , rigidly secured thereto and connected by a link m^8 to a wrist-pin m^9 on a gear m^{10} , the latter being engaged by a pinion m^{11} , rotary with the pulley m^{12} , said pulley being driven by a band m^{13} from another pulley m^{14} , fast on the main shaft B. The pulley m^{12} and pinion m^{11} are both fast on a short shaft m^{15} , which turns in a bracket m^{17} , bolted to an upright part a' of the frame A. 70

In order that the distance which the tension moves be regulated and that the speed of its movement toward and from the drop-wire may be adjusted, the arm m^7 of the tension rock-shaft is provided with a plurality of holes m^{16} at different distances from said rock-shaft, in either one of which holes the stud or bolt m^{18} , which connects the upper end of the link m^8 to said arm, may be inserted. 75

Obviously the rotation of the shaft B causes the tension to move alternately toward 80 and from the drop-wire H. The parts which contribute to rock the rail will be so proportioned as to move the tension toward the drop-wire H at a speed not exceeding the normal feed of the yarn, so as not to slacken the 85 yarn when running.

When a knot or bunch is wedged in the scraper, the yarn is slackened, as indicated by dotted lines in Fig. 1, at the next movement of the tension toward the drop-wire, allowing 90 the drop-wire to fall into the path of a projection j on the knock-off wheel J, causing the rear end of the drop-wire holder to be lifted above the foot g^4 of the arm g^3 of the slide G, whereupon the weighted end of the lever F is depressed and the front end of said lever is raised, lifting the cradle and moving the cop out of contact with the drum D, said cop then coming to rest immediately. 95

I claim as my invention—

1. The combination of a tension device, a knot-arresting yarn-scaper, winding means for drawing a yarn successively through said tension device and said scraper, a drop normally suspended on said yarn between said tension device and said scraper, automatic means for slackening said yarn between said tension device and said scraper, when the progress of said yarn is interrupted by a knot or bunch at said scraper, to permit the falling 110 of said drop, and means operated by the falling of said drop to stop the winding of said yarn. 115

2. The combination of a tension device, a knot-arresting yarn-scaper, winding means for drawing yarn successively through said tension device and said scraper, a drop normally suspended on said yarn between said tension device and said scraper, automatic means for continuously alternately shortening and lengthening the distance between said tension device and said scraper, to slacken said yarn between said tension device and said scraper when the progress of said yarn is interrupted by a knot or bunch at said scraper, 120 125 130

to permit the falling of said drop, and means operated by the falling of said drop, to stop the winding of said yarn.

3. The combination in a winding-machine, 5 of a cop-holder, means of rotating the same, a stop-motion therefor, a tension device, a knot-arresting yarn-scaper, a drop normally suspended by the tension of the yarn or thread passing through said tension device and said 10 scraper, means for operating said stop-motion by the falling of said drop, and automatic means for continually varying the distance between said scraper and said tension device.

4. The combination of a driving - drum, 15 means for rotating the same, a cop-holder normally rotated by frictional contact between said drum and said holder or cop, a knot-ar-

resting yarn-scaper, a rock-shaft, means for rocking the same, a tension device rigidly secured to said rock-shaft and vibrated by the 20 rocking of the same, means for moving said cop-holder with its cop away from said drum, said last-named means being normally prevented from operation by the drop supported by a yarn passing between said tension device and said scraper and operated upon the 25 falling of said drop by the slackening of said yarn, and said drop.

In testimony whereof I have affixed my signature in presence of two witnesses.

CLARENCE N. CHILDS.
